UNITED STATES PATENT OFFICE.

GERHARD STOCKEL, OF CHICAGO, ILLINOIS, ASSIGNOR TO IRA H. MILLER, OF CHICAGO, ILLINOIS.

TOY SAVINGS BANK.

Application filed February 4, 1922. Serial No. 534,048.

To all whom it may concern:

Be it known that I, GERHARD STOCKEL, a citizen of the United States, and a resident of Chicago, in the county of Cook and State 5 of Illinois, have invented certain new and useful Improvements in Toy Savings Banks, of which the following is a specification.

This invention relates to improvements in toy savings banks, and more particularly to 10 banks which may be distributed by banking institutions as an inducement to save money, and to deposit the savings in a savings account at such banking institution.

The object of this invention is to provide 15 a novel savings bank or coin receptacle, which, by its form and appearance, will appeal particularly to younger persons, and therefore sustain their interest in its purpose. It is conceived that making the receptacle spherical in shape, and having the size and appearance of a playing ball, such as a baseball, a greater interest and desire to save will be created, by reason of the suggestion of, and association with, other 20 things in which the person is interested.

A further object of the invention is to provide a simple, yet secure receptacle, sufficiently strong to resist breakage, as well as the efforts of a person to break into the 25 bank after the savings have been inserted.

In the drawings, a preferred construction of a bank embodying the invention is disclosed, the figures thereof being briefly described as follows:

25 Figure 1 is a view in elevation of the bank, showing the coin receiving slot, and showing its relation to the equator or parting line of the two hemispheres making up the bank,

30 Figure 2 is another view of the bank taken substantially at right angles to the position shown in Figure 1, and further showing the lower hemisphere in elevation,

35 Figure 3 is a perspective view showing the internal construction of the upper hemisphere,

Figure 4 is a perspective view of the lower hemisphere, showing the interior thereof,

40 Figure 5 is a cross-sectional view of the sphere taken thru its axis, as indicated by line 5—5 of Figure 1,

Figure 6 is an enlarged detailed view in cross-section taken on line 6—6 of Figure 5,

45 Figure 7 is a perspective view of the small

circular plate which is applied to the lower 55 hemisphere, and over the adjacent end of the internal axial post, and

Figure 8 is a perspective view of a suitable key to be used in unlocking the receptacle. 60

As a preferable construction, and as hereinbefore suggested, the bank embodying the invention comprises a hollow spherical body made up of two semi-spherical sections or hemispheres, which may be conveniently 65 termed an upper hemisphere 1, and a lower hemisphere 2. These hemispheres have abutting engagement at their edges which form an annular parting line or an "equator" 70 3. As clearly shown in Figure 4, the edge of one of the hemispheres, preferably the lower hemisphere 2, is reinforced by a metallic ring or band 4 having an annular flange 4^a which projects slightly beyond the edge of the hemisphere. 75

When these hemispheres are placed together, they form a perfect sphere adequately reinforced about its equator by means of the ring 4, the flange 4^a of the latter forming with the edge of the lower 80 hemisphere, a shoulder or seat for the corresponding edge of the upper hemisphere 1. Extending at right angles to the plane of the equator 3, and in alignment with the axis passing thru the "poles", is a post consisting of two sections 5 and 6, likewise 85 parted substantially in the plane of the equator, and each being permanently fixed to its respective hemisphere 1 and 2. The section 5 of the post connected with the upper hemisphere 1 is hollow or tubular substantially throughout its length, there being formed a comparatively large bore 5^a extending from its outer end to within a short 90 distance of its inner end, and a comparatively small bore 5^b extending throughout the remaining portion. As clearly shown in Figure 5, the bores 5^a and 5^b are adapted to receive a small screw or screw threaded stud 95 7, the shank or threaded portion thereof extending through and beyond the inner end of the post section 5, and having screw threaded engagement with the tapped socket 6^a in the end of the post section 6. The stud 7 is provided with a key receiving shank 7^a, 100

which is preferably triangular in cross-section, as clearly shown in Figure 6. Intermediate the threaded key receiving shank

portions of the stud is a collar 7^b substantially the same diameter as the larger bore 5^a, and adapted to limit the endwise movement of the stud within the post section 5, and to bear against the shoulder formed at the lower end of the larger bore 5^a, thereby effecting the drawing together of the post sections when the stud is rotated. It is also to be observed that the key receiving portion 7^a of the stud is located near the lower end of the large bore 5^a, and a distance inwardly from the surface of the sphere. To reach the stud for the purpose of removing the same, a special key 8 is provided, the same having a shank of suitable length, and with a triangular shaped socket 8^a at the end thereof adapted to engage the correspondingly shaped head 7^a of the stud 7. The ends of the post sections are fixed to the hemispheres in any suitable manner, the tubular post section 5 having its opening flush with the surface of the sphere, whereas the outer end of the post 6 is treated in a somewhat different manner, the end being provided with a reduced portion which fits an opening formed in the lower hemisphere, and secured in position by upsetting the reduced end of the post. Furthermore, an annular portion of the hemisphere immediately surrounding the end of the post section 6 is depressed inwardly as at 9, Figure 5, and a circular plate 10 is fitted within this depression so that its outer face is flush with the surface of the sphere. This plate 10 is provided with oppositely disposed fingers 10^a which are bent at right angles and inserted in openings cut through the hemisphere, and then crimped down in the manner clearly shown in Figure 5. This plate not only covers the exposed extremity of the internal post section 6, but also forms a tag or name plate on which may be stamped the name of the banking institution issuing the receptacle, or other information that may be desired.

Within the upper hemisphere, and extending at right angles to the equator 3 is a coin receiving slot 11 of suitable length and width to receive coins of several denominations. The lower end of the slot 11 terminates adjacent to the edge of the upper hemisphere 1, and a portion of the metal removed to form a slot is bent downwardly or doubled back against the inner surface of the hemisphere to form a lug 12 immediately at the edge of said hemisphere. This lug is adapted to engage a single notch 13 cut in the edge of the opposite or lower hemisphere, thereby providing a lock against the relative rotation of the hemispheres about their common axis, and the resulting unscrewing of the stud which would otherwise result.

Within the interior of the upper hemisphere and extending over the slot 11 is a guard member 14 consisting of a strip of

spring metal bent or curved to correspond to the curvature of the hemisphere, and extending from the upper end of the post 5 in alignment with the slot 11, and terminating just short of the lower extremity thereof. Within the guard member 14 is formed a slot 15 adapted to register with, though slightly offset lengthwise of, the coin receiving slot 11. The guard strip is secured within the upper hemisphere and adjacent the pole thereof in any suitable manner, such as riveting or soldering, although in Figure 5 it is shown as surrounding and fitting within a shoulder formed at the upper end of the post section 5, and secured against the inner surface of the wall of the hemisphere. The function of the guard is to prevent coins from escaping through the receiving slot 11 after they have been inserted in the bank, but at the same time it does not prevent other coins from passing through the slot into the bank. In inserting the coin through the slot 11, it engages the lower extremity of the slot 15 in the guard, and the upper edge of the slot 11, thereby springing the guard member inwardly until the coin is completely free, and then drops into the receptacle through the inner slot 15. Manifestly the guard member springs back into position, thereby preventing the escape of coins from the interior.

The two hemispheres which form the spherical receptacle are preferably made of a thin metal, and in order to make the receptacle more attractive, it is preferably coated with enamel to represent the color of an ordinary baseball, and markings such as 16 (Figures 1 and 2) are reproduced on the surface to represent the stitching of a baseball. Furthermore, the diameter of the receptacle is preferably that of a regulation baseball, so that the resemblance thereto may be carried out in every possible detail.

Having described the construction and function of the device herein illustrated, I claim as my invention:

1. A receptacle comprising semi-spherical sections adapted to be joined together to form a sphere, and means for locking said sections together comprising an internal post extending axially between the poles of said sphere, and consisting of sections in abutting contact parted adjacent the center thereof, and a locking member connecting the abutting ends of said post sections and operated by a key insertable through a bore extending axially from the outer end of one of said post sections.

2. A receptacle in the form of a sphere comprising semi-spherical portions, and means for connecting said portions together, comprising axial post sections secured at the poles and having abutting engagement at the center of the sphere and a screw stud connecting the abutting ends of said post

sections, operated by a key insertable through a bore extending axially from the outer end of one of said post sections.

3. A receptacle comprising semi-spherical sections adapted to be joined together to form a sphere, means for reinforcing said sphere axially and circumferentially, comprising post sections anchored to said semi-spherical sections and extending axially between the poles and having abutting contact at the center thereof, and a ring extending around the edge of one semi-spherical section and forming a seat for the edge of the other section, and a locking member connecting the abutting ends of said posts and operated by a key insertable through a bore extending axially from the end of one of said post sections.
4. A receptacle in the form of a sphere comprising semi-spherical portions, an internal ring surrounding the edge of one of said portions, and forming therewith a shoulder for the edge of the other portion, a post extending axially of said sphere, and divided into sections having abutting engagement at the center of the sphere, and a screw stud connecting said post sections at their abutting ends, and operated by a key insertable through a bore formed in one of said post sections.

5. A receptacle of spherical conformation comprising semi-spherical sections meeting at the equator with edges in abutting engagement, a ring of L-section surrounding the internal edge of one section and having a flange bearing flatwise around the marginal portion thereof and forming a projecting shoulder telescoping with the marginal

portion of the other of said sections, and an internally projecting lug on said last mentioned section engaging a notch in said ring for locking said sections against relative axial rotation.

6. A receptacle of spherical form comprising semi-spherical portions joined together at the equator with edges in abutting engagement, a circumferential reinforcing ring around the inner edge of one of said portions, and comprising a flange providing a seat for the edge of the other portion, a coin receiving slot in one of said portions, a flexible guard member extending over the inside of said coin receiving slot, means for separably joining said portions comprising a post divided at the center thereof, and a fastening member insertable from one end of said post, and means for locking said portions from relative rotation.

7. A receptacle of spherical form comprising semi-spherical portions abutting at their edges, means for reinforcing said portions axially and circumferentially, comprising a post parted at its central point, and an internal ring surrounding the equator, a locking lug on one portion engaging a notch in said ring, for locking said portions from rotation, and a screw stud insertable axially through a bore in said post, connecting the parts of said post at the center of the sphere, and adapted to be manipulated by a key fitting said bore, and engaging said stud.

In witness whereof, I hereunto subscribe my name this 28th day of January, A. D., 1922.

GERHARD STOCKEL.
